UNITED STATES PATENT OFFICE.

DAVID H. COUCH, OF WARWICK, RHODE ISLAND.

ROTARY DRIER.

Application filed March 25, 1926. Serial No. 97,316.

This invention relates to rotary driers and particularly to a type of drier consisting of a double walled shell heated by a hot fluid circulated between the walls.

5 A particular object of my invention is to provide a means for drying coal or other material in large quantities without the use of direct fire.

10 Another object of my invention is to provide a type of drier which may be installed in any desired location without the necessity of having a furnace connected directly to the drier, thus making it possible to install the drier in locations where it would be impossible to locate it if an integral furnace were to be installed.

15 Also a further object of my invention is to provide a drier of very large capacity suitable for drying coal for large power plants using pulverized coal.

20 Other objects will appear in the following specification and in the claims appended thereto.

25 The preferred embodiment of my invention is shown in the drawings and consists of an outer shell, an inner shell preferably made up of helical grooves or corrugations forming one or more continuous threads from one end of the shell to the other, the 30 object of said threads or corrugations being to present a greater drying surface and provide a means for rapidly moving the material thru the drier, and hollow hubs connected to and communicating with the inner 35 space between the shells by means of hollow spokes. These hollow hubs and spokes form the ports of entrance and discharge of the heating fluid which is forced thru the heating spaces between the inner and outer shells.

40 As a heating medium, many kinds of liquids or even gases may be used, but for most purposes I prefer to use an oil of high flash point such as is sometimes used in industrial heating, this oil being heated by suitable external means and pumped thru the heating space between the shells. Any suitable liquids or even gases may be employed as heating fluids, but since a gas has a low specific heat and low density and since there 45 would be a low transfer rate between a gas and the metal plates of the drier, heated liquids are preferable. In the following description the term "liquid" will be used instead of the general term "fluid."

50 The preferred design of my invention is

illustrated in the accompanying drawings wherein:—

Fig. 1 is a vertical longitudinal section thru the centre of the drier.

Fig. 2 is an end elevation of a three- 60 groove or flight drier.

Fig. 3 is a side elevation showing a general assembly of the drier and one system of heating and circulating the heating liquid.

Figs. 4 and 5 are vertical sections at right 65 angles to one another of the liquid control valve gear for causing the liquid to flow thru each channel in definite rotation, and

Fig. 6 is a vertical longitudinal section of the revolving joint between the drier and 70 the stationary liquid supply piping. This revolving joint is shown as a part of an elbow which forms a suitable anchorage for holding the shaft of the cam which operates the valves. It is not essential, however, that 75 this member be in the form of an elbow, but it may take any desired form.

Referring now in detail to the several figures, the numeral 1 represents the outer shell of the drier which is preferably cylindrical 80 and provided with a ring gear 2 by means of which the drier is rotated by a gear 3 on a suitably driven power shaft 4. Within the shell 1, and preferably supported thereby, is an inner shell 5, having a spirally 85 corrugated surface, the space between the outer shell and the helices of the inner shell forming a chamber through which the heating liquid circulates. Each helix forms a single spiral thread, continuing throughout 90 the length of the shell forming a spiral passage for the circulation of the heating liquid. In the present instance there are three parallel helices which open in the plane of the front of the drier (the left-hand end in 95 Figs. 1 and 3) as arcuate spaces 6, 7 and 8, each covering an angular distance of substantially 120° and being separated from one another by the partitions 9 representing the wall of the inner shell. The internal 100 corrugations of the inner shell serve as flights for conveying the material to be dried from the forward to the discharge end of the drier, and also afford a large surface for exposure of the material to the heating 105 medium.

Heating liquid is supplied to the drier from a suitable source, such as a boiler 40 Figure 3, through a pipe 10 and a revolving connection consisting of a stationary elbow 110

11 and an axially arranged conduit 12 revolubly connected to said elbow in a manner presently to be explained. The axial conduit 12 is in communication with a hollow hub 13 having radial distributing branches 14 leading each to one of the spiral passages 6, 7 or 8. The heating liquid leaves the drier through branch conduits 15 each communicating with one of the spiral passages 6, 7 and 8 and with a hollow hub 16 with which the discharge conduit 17 communicates, the latter being part of a revolving joint shown in detail in Figure 6. This revolving joint comprises a fixed elbow 18 to which the discharge conduit 17 is swivelly connected by structure similar to that shown in connection with the elbow 11. This joint is preferably established by forming the ends of the conduit 17 and elbow 18 with spherical portions 19 and 20, respectively, one seated within the other as shown in Figure 6. A clamping ring 21 surrounds the spherical swell upon the stationary elbow and is formed with a spherical seat engaging said elbow. The clamping ring is held in resilient engagement with the spherical swell on said fixed elbow by means of bolts 22 passing through flanges on said ring and on the spherical part of the conduit 17, said bolts being provided with springs 23 normally held in compression, and which draw the ring 21 and flange of the spherical portion 19 together and thus urge the spherical seat portions 20 and 19 of the elbow 18 and conduit 17 into fluid-tight engagement.

The present invention contemplates the supplying of heating fluid successively and in rotation to the three spiral passages, for which purpose it is necessary to have some form of valve control to govern the admission of the liquid. I have therefore devised simple valve mechanism shown in detail in Figure 4 and which is perhaps most conveniently located within the hollow hub 16 at the discharge end of the drier. The branch conduits 15 are each provided with a valve closure 25 mounted on a stem 26 which passes through a transverse guide member 27 arranged in the mouth of the conduit and also through a cylindrical guide member 28 suitably perforated, and forming a part of the hub 16. Said cylindrical guide member acts as a stop to limit the extent of opening of the valve closures 25. Said valve closures are opened by the pressure of the heating liquid in the drier, and are positively closed by means of a cam 29. A spring 30 surrounds the valve stem 26 of each valve closure and holds the parts tensioned so as to avoid noise and lost motion. The cam 29 opens the valve closures in rotation. It is essential that the cam be stationary, the hub 16 with the branch conduits and valve closures revolving around it. The cam is therefore mounted upon a rod 31 which extends

through the valve conduit 17 and fixed elbow 18, one end of said rod being arranged in a socket 32 formed at the back of said elbow. The rod is prevented from rotating by means of a pin 33 passing through a slot 70 in the end of the rod 31. The hub 16 is formed with an axial projection 34, having a reduced end 35 which enters a recess in the cam, affording support for the latter. A spring 36 is compressively housed in a cap 75 37 secured to the socket 32 of the elbow 18, said spring bearing against the end of the rod 31 for pushing said rod longitudinally and thus moving the cam 29 into engagement with the reduced end 35 of the projection 80 34, the slot in said rod permitting this movement.

Aside from the valve gear just described, the discharge connections are exactly the same as the inlet connections, the liquid being received from the hollow hub 16 through the elbow 18 by the liquid return line 38, which conveys the liquid to pump 39. Said pump 39 forces the liquid thru the heater 40 and back thru the pipe connection 10 thru the drier again, thus keeping up a continuous circulation of the heating liquid. Continuous circulation is not, however, an essential feature as there might be some cases where the liquid would be forced thru the drier only once and then used for some other purpose, or disposed of as waste.

By forming the inner shell 5 with a plurality of helices and thus forming a corresponding number of spiral passages between the inner shell 5 and the outer shell 1 for the circulation of the heating liquid, not only will the apparatus be capable of treating a greater quantity of material within a given time, but it will also more effectively and uniformly heat such material than would be the case if the inner shell were provided with only a single continual helix to form a single continuous spiral passage between the inner and outer shells. This is because a plurality of internal spiral threads on the inner shell 5 will cause the material to move from one end to the other of the apparatus more rapidly and the heating fluid will be caused to pass more rapidly from one end to the other of the apparatus through each of the plurality of spiral passages than would be the case if there was only a single helix and a single continuous spiral passage within the same space. Further, since the heating fluid will move more quickly from one end to the other of each of the plurality of spiral passages than it would move from one end to the other of a single spiral passage, there will be less reduction in its temperature at the outlet end of each passage than there would be if only a single continuous spiral passage were provided, because in the former case, there would be a plurality of comparatively short

passages, whereas in the latter case there would be a single long passage.

By providing each of the plurality of spiral passages with a separate inlet through which inlets the heating liquid is permitted to flow successively, the treated material will be more uniformly heated than would be the case if the liquid was supplied to all of said passages simultaneously, because in the latter case, if the pressure of the heating fluid be low, it might be disposed to flow entirely or at a more rapid rate through one of the passages, or, if the heating fluid be supplied under the proper pressure and one or more of the passages becomes partially obstructed, the heating liquid would be disposed to flow entirely or more rapidly through that passage or those passages which offered the least resistance to its flow.

20 The drier is supported by and rotates on the circular tires 41 and 42 which roll on roller wheels 43 and 44, as is usually the case with rotary driers. These roller wheels turn in bearings 45 supported by or forming a part of the bed-plates 46 and 47. These bed-plates are in turn supported on the foundation piers 48 and 49.

25 Roller wheels 50 and 51 bear on the edges of the tire 41 and thus hold the drier in longitudinal alignment during rotation.

30 The entire outer surface of the drier except the surface in contact with the tires 41 and 42, and the driving gear 2 is heavily lagged with insulating material 52 to prevent as much as possible the loss of heat by radiation and convection from the outer shell 1. A shroud ring 53 is attached to the inlet end of the drier by welding or other suitable means. This ring acts as a receiving chamber for the material to be dried and feeds it to the helices as the drier revolves.

35 Coal or other material to be dried enters thru the spout 54, and after being heated in the drier falls therefrom into the discharge hopper 55 from which it passes to the discharge pipe 56. A hood 57 which is preferably continuous with the discharge hopper and surrounds the upper half of the exit end of the drier communicates with the vent or chimney 58 and serves as a means of ventilating or carrying away the moisture driven off in the drier. 59 is a damper at the base of the ventilating stack to regulate the amount of draft.

40 55 It is preferable to have a flared ring 60 attached by welding or other suitable means to the discharge end of the drier to properly discharge the material passing thru the drier into the hopper 55.

60 65 The channels for the heating liquid are vented by valves 61 to allow the escape of entrapped air when such channels are filled with the heating liquid and, when desired, to discharge any gases which may accumulate. A vent line 62 is also provided for the

purpose of continually ridding the system of gases or vapors. 63 is an expansion tank which allows for the cubical expansion of the heating liquid and contains a reserve supply of liquid to replace losses from evaporation or other causes. An overflow tank 64 is provided in case the expansion tank 63 should overflow, said tank being connected with the expansion tank by a vented pipe 65. Excessive pressure in the circulating system is prevented by the relief valves 66 and 67, by-pass 68 and pipe 69, and also by the vent line 62.

70 While I have in the above description disclosed what I believe to be a preferred and practical embodiment of my invention, it is to be understood that the specific details described are not limitative in their effect upon the invention but merely illustrative except in so far as they are expressly prescribed by the terms of the appended claims.

75 Having described my invention what I claim as new and desire to secure by Letters Patent, is:

80 1. A rotary drier including outer and inner shells, the inner shell having a plurality of internal and external spiral corrugations, said inner and outer shells forming between them a plurality of spiral passages for the flow of heating fluid and the internal corrugations of the inner shell serving to move material lengthwise thereof, said inner shell having at one end an inlet for the material to be treated and at its opposite end an outlet for said material.

85 2. A drier including outer and inner shells, the latter being provided with a plurality of parallel spiral corrugations, forming between the inner and outer shells a plurality of spiral passages for the flow of heating fluid, and means for supplying heating fluid in rotation to said passages.

90 3. A rotary drier including outer and inner shells, the latter being provided with a plurality of parallel spiral corrugations, forming between said outer and inner shells a plurality of passages for the flow of heating fluid, and means controlled by rotation of said drier for admitting heating fluid in rotation to said passages.

95 4. A rotary drier including outer and inner shells, the inner shell being provided with a plurality of spiral corrugations forming a plurality of spiral passages for the flow of heating fluid, a conduit including a hub and axial portion, and branch conduits distributing fluid to said passages, a supply pipe, and a revoluble joint connecting said supply pipe and axial portion.

100 5. A rotary drier including outer and inner shells, the latter being provided with a plurality of spiral corrugations forming a plurality of passages for the flow of heating fluid, conduits arranged adjacent the ends of said drier including, respectively,

inlet and discharge hubs and branch conduits communicating with the several passages, means for supplying heating fluid to said inlet hub, and means controlled by rotation of said drier for permitting the flow of heated liquid in rotation through said passages.

6. A rotary drier including means for directing the flow of heated liquid thereabout in definite separate passages, and means controlled by rotation of said drier for admitting liquid in rotation to said passages.

7. A rotary drier including a plurality of spiral passages formed thereabout to direct the flow of heating fluid, supply and discharge pipes, and conduits connected to said supply and discharge pipes, said conduits having passages communicating with said passages, valves controlling one set of branch conduits, and means operative responsive by rotation of said drier for controlling the admission of heating fluid in rotation to said passages.

8. A rotary drier including a plurality of

parallel spiral passages formed thereabout to direct the flow of heating fluid, supply and discharge pipes and conduits connected thereto having branches communicating with said passages, valves in one of said conduits controlling one set of branch conduits, and means operative responsive to rotation of said drier for controlling the admission of heating fluid in rotation to said passages.

9. A rotary drier including a plurality of parallel spiral passages formed thereabout to direct the flow of heating fluid, supply and discharge pipes and conduits swivelly connected thereto having branches communicating with said passages, valves in one conduit controlling one set of branch conduits and a stationary cam for actuating said valves as the latter travel about said conduit responsive to rotation of said drier.

In testimony whereof I have hereunto set my hand.

DAVID H. COUCH.
